(Cl. D41—1)

FIG. 1

FIG. 2

FIG. 3

To all whom it may concern:

Be it known that I, Louis Charles Smalley, a citizen of the United States, residing in York, in the county of York and State of Pennsylvania, have invented a new, original, and ornamental Design for a Vehicle Jack, of which the following is a specification, reference being had to the accompanying drawing, forming part thereof.

In the drawing:

Fig. 1 is a side elevation of a vehicle jack embodying my new design and showing the vehicle engaging members in elevated position.

Fig. 2 is a top plan view of the vehicle jack shown in Fig. 1 but illustrating the vehicle engaging members in inoperative or lowered position.

Fig. 3 is a perspective view of the vehicle jack shown in Figs. 1 and 2 and illustrating the vehicle engaging members in inoperative or lowered position as in Fig. 2.

I claim:

The ornamental design for a vehicle jack, as shown.
